J. WHITE.
Spark-Arresters.

No. 142,308.

Patented August 26, 1873.

UNITED STATES PATENT OFFICE.

JAMES WHITE, OF SOUTH AMBOY, ASSIGNOR TO HIMSELF AND CHARLES S. WORTS, OF JAMESBURG, NEW JERSEY.

IMPROVEMENT IN SPARK-ARRESTERS.

Specification forming part of Letters Patent No. **142,308**, dated August 26, 1873; application filed July 25, 1873.

To all whom it may concern:

Be it known that I, JAMES WHITE, of South Amboy, Middlesex county, State of New Jersey, have invented an Improved Spark-Arrester, of which the following is a specification:

The object of my invention is to arrest the sparks of a locomotive-boiler and to return them to the fire-box by introducing into the smoke-box a perforated partition, *a*, as shown in the accompanying drawing, representing a vertical section of a locomotive steam-boiler, the sparks arrested by the partition being forced by the aid of a jet of live steam through a passage, *b*, into the fire-box *D* above the grates-bars, and the passage being provided with a valve, *e*, for closing the said passage when the jet of steam is discontinued.

The boiler is, as regards its general structure, similar to ordinary locomotive-boilers; but the smoke-box instead of inclosing a single chamber is separated into two compartments, *m* and *n*, by the partition *a*, which may consist of strong wire-gauze or of a perforated plate. The above-mentioned passage *b* forms a communication between the chamber *n* of the smoke-box and the fire-box *D*, and within this passage is a nozzle, *h*, directed toward the fire-box and forming the termination of a pipe, *G*, which communicates with the steam-space of the boiler, and should be furnished with a cock to be operated by the attendant engineer. The passage *b* contains near its smoke-box end a clack-valve, *e*, which opens toward the fire-box.

The sparks and particles of fuel passing from the tubes of the boiler strike against the partition *a* (through which none but the smallest particles can pass) and drop to the bottom of the chamber *n*, whence they are forced by the action of the steam-jet, when the cock of the pipe *G* is open, through the passage *b* into the fire-box at such a point above the grates-bars that the particles will be brought into contact with the burning fuel, and will be consumed by the same. As long as the jet of steam is continued the valve *e* will remain open, but on closing the cock of the pipe *G* the valve will be closed, and will prevent the escape of sparks or products of combustion through the passage *b* to the chamber *n*.

I claim as my invention—

1. The combination, in a locomotive-boiler, substantially as described, of a perforated or wire-gauze partition, *a*, in the smoke-box, a passage, *b*, between the smoke-box and fire-box, and a nozzle, *h*, directing a jet of live steam through the said passage *b* toward the fire-box.

2. The combination described of the passage *b* between the chamber *n* and the fire-box with a steam-nozzle, *h*, and a valve, *e*, opening toward the said fire-box.

In testimony whereof I have signed my name to this specification in the presence of two subscribing witnesses.

JAMES WHITE.
